UNITED STATES PATENT OFFICE.

GEORGE S. GOODALE, OF HOUGHTON, MICHIGAN.

EXTENSION-FITTING FOR LEVELING-RODS.

SPECIFICATION forming part of Letters Patent No. 707,225, dated August 19, 1902.

Application filed December 9, 1901. Serial No. 85,275. (No model.)

To all whom it may concern:

Be it known that I, GEORGE S. GOODALE, a citizen of the United States, residing at Houghton, in the county of Houghton and State of Michigan, have invented certain new and useful Improvements in Extension-Fittings for Leveling-Rods; and I do declare the following to be a full, clear, and exact description of the invention, such as will enable others skilled in the art to which it appertains to make and use the same.

This invention relates to an extension-rod fitting for civil engineers' leveling-rods.

The object of the invention is to provide a quick-setting fitting which shall be simple of construction, durable in use, comparatively inexpensive of production, and which may be easily and expeditiously set to exact adjustment.

With this and other objects in view, which will readily appear as the nature of the invention is better understood, the same consists in certain novel features of construction and combination and arrangement of parts, as will be hereinafter more fully described, defined in the appended claims, and illustrated in the accompanying drawings, in which—

Figure 1 is a section through the parts of the fitting on line 1 1 of Fig. 2, the back leveling-rod appearing in rear elevation. Fig. 2 is a section on line 2 2 of Fig. 1, the leveling-rods appearing in side elevation with the front rod partly broken away to expose the fastenings securing the casing thereto. Fig. 3 is a view of the cover-plate, and Fig. 4 is a detail view of the clamping-collar and screw.

In the drawings, 1 denotes the front leveling-rod, and 2 the back leveling-rod, the latter being provided in practice with a scale (not shown) upon its outer face.

To the rod 1 is fixed a casing 3, which is open at its upper end and outer side and is provided with a cover or plate 4, which closes said outer side. This plate is provided with an observation-opening 5 and a scale 6 to co-operate with the scale upon the back rod 2 through the said visual opening 5.

The rod 2 is mounted to slide through the casing 3 and is encompassed by a collar 7, carrying a set-screw 8, which works through

a screw-threaded aperture 9, formed in the collar, and engages the stem 10 of a spring-plate 14, which is adapted to be forced by the screw against the rod 2 to lock said rod in 55 adjusted position.

The collar 7 is carried by a depending frame 15, which fits and slides within the casing 3 and encompasses the outer face and sides of the rod 2. The base or lower portion of this 60 frame is formed with a threaded opening 16, through which works the threaded end 17 of an adjusting-screw 18. The screw works through a smooth aperture 19, formed in the casing 3, and is swiveled to said casing by 65 forming the screw with a fixed collar 20, which is held against longitudinal movement by a plate 21. This plate 21 is connected by pins or screws 22 with the casing and with a split clamping-collar 23, having lateral lugs 24, 70 formed with threaded apertures for the reception of the screw-threaded end 25 of an auxiliary adjusting-screw 26.

In operation when it is desired to adjust the fitting the rod 2 is slid through the casing to within approximately three-eighths of an inch of the desired adjustment, and the collar 7 is then locked thereto by operating the screw 8 to cause the spring-plate 14 to bear against said rod. Then by operating the 80 screw 18 the sliding frame 15 may be moved to set the rod to the exact adjustment. After this has been done the screw 26 is operated to cause the collar 23 to tightly grip or clamp the screw 18 to hold it against movement, by 85 which the parts are prevented from being disturbed by blows or shocks and moved out of exact adjustment.

From the foregoing description, taken in connection with the accompanying drawings, 90 the construction, mode of operation, and advantages of the invention, it is thought, will be readily apparent without requiring an extended explanation.

While the preferred form of the invention 95 is as herein described, it will of course be understood that various changes in the form, proportion, and the minor details of construction may be resorted to without departing from the principle or sacrificing any of the advantages thereof.

I claim—

1. The combination with the front and back leveling-rods; of a casing fixed to the front rod and through which the back rod slides, a collar slidably mounted upon the back rod 5 above said casing, a frame sliding in the casing and fixed to the collar, a fastening carried by the collar for locking it in adjusted position on the back rod, and a screw swiveled to the base of the casing and working in said 10 frame for setting the rod to exact adjustment after the collar has been locked thereto, substantially as set forth.

2. The combination with the front and back leveling-rods; of a casing fixed to the front 15 rod and through which the back rod slides, a collar mounted to slide upon the back rod above the casing, a frame sliding in the casing and to which the collar is connected, means for locking the collar in adjusted position, a screw swiveled to the bottom of the 20 casing and operatively connected to said frame for setting the rod to exact adjustment after the collar has been locked thereto, and means upon the casing for locking said screw

in adjusted position, substantially in the 25 manner set forth.

3. The combination with the front and back leveling-rods; of a casing fixed to the front rod and through which the back rod slides, a collar slidably mounted upon the back rod 30 5 above said casing, a frame sliding in the casing and fixed to the collar, a fastening carried by the collar for locking it in adjusted position on the back rod, an adjusting-screw connecting the casing and sliding frame for adjusting the sliding frame, said screw having a collar swiveled in an aperture in the bottom of the casing, a plate closing said aperture, and means upon said plate for locking the screw in adjusted position, substantially 35 40 as set forth.

In testimony whereof I have hereunto set my hand in presence of two subscribing witnesses.

GEO. S. GOODALE.
